US0D1048178S

(12) **United States Design Patent** (10) **Patent No.:** **US D1,048,178 S**
(45) **Date of Patent:** **** Oct. 22, 2024**

(54) **BEAD SPINNER SET**

(71) Applicant: **Shenzhen Spyao Technology Co., LTD**, Guangdong (CN)

(72) Inventor: **Fulin Hu**, Guangdong (CN)

(**) Term: **15 Years**

(21) Appl. No.: **29/946,186**

(22) Filed: **Jun. 6, 2024**

(51) **LOC (14) Cl.** **19-06**

(52) **U.S. Cl.**

USPC **D19/111**

(58) **Field of Classification Search**

(57) **CLAIM**

The ornamental design for a bead spinner set as shown and described.

DESCRIPTION

FIG. 1 is a perspective view of a bead spinner set showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

The broken lines depict portions of the bead spinner set and form no part of the claimed design.

1 Claim, 8 Drawing Sheets
